UNITED STATES PATENT OFFICE.

WILHELM B. BRONANDER, OF MONTCLAIR, NEW JERSEY, ASSIGNOR TO AMERICAN MACHINE & FOUNDRY COMPANY, A CORPORATION OF NEW JERSEY.

VALVELESS PUMP OR COMPRESSOR.

Application filed February 3, 1926. Serial No. 85,643.

This invention relates to an improvement in valveless pumps or compressors; and it has for its main object the production of a simple and durable device of this character that will operate powerfully but quietly. With this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a sectional elevation of a pump or compressor constructed in accordance with the invention; Fig. 2 is a sectional view taken on the line 2-2 in Fig. 1; Fig. 3 is a cross-sectional view taken on the line 3-3 in Fig. 2; and Figs. 4 to 9 inclusive are diagrammatic views illustrating the operation of the device.

In carrying the invention into effect, there is provided a cylinder which may be open at both ends. This cylinder is provided with an inlet port and an outlet port in its wall, one on either side of its mid-section. There are further provided two pistons working in said cylinder, and means for producing relative differential retreating movements of said pistons in the region of said inlet port, whereby the gas or liquid is drawn into said cylinder, and for producing relative differential approaching movements of said pistons in the region of said outlet port, whereby the gas or liquid is forced out of said cylinder, the charge of gas or liquid being transported from the region of said inlet port to the region of said outlet port by a relative differential traveling movement of said pistons. Although a single crank-shaft with well-known connections may be used for producing these movements, in the best constructions contemplated, two cranks and operative connections are employed for this purpose, said cranks being driven at the same speed and in the same direction of rotation but with one having a lead over the other, in order to produce the necessary differential movements of the pistons. The specific structure selected to illustrate the invention is but one of numerous possible concrete embodiments of the

same; and the invention, therefore, is not to be restricted to the precise details of the structure shown and described.

Referring to the drawings, Figs. 1 to 3, the cylinder 10 has an inlet port 11 and an outlet port 12 in its wall. The left-hand piston 13 is connected by a rod 14, pivotally attached to it by means of a wristpin 15, to a crank 16 supported by the discs 17-17 of a crankshaft 18. Similarly, the right-hand piston 19 is connected, by means of a rod 20, pivoted on the wristpin 21, to a crank 22 carried by the discs 23-23 of a crankshaft 24. The two crankshafts are housed in crankcases 25-25 which also support the ends of the cylinder 10. Each crankcase has a side cover 26 for the insertion of the crankshaft, and a hand-hole cover 27 for attaching the connecting rod to the crank.

Each of the crankshafts 18 and 24 carries a worm-wheel 28 driven by a worm 29 the shaft 30 of which is supported by a split housing 31 attached to one side of the crankcase. The worm shafts 30 are connected, by couplings 32, to the shaft of an electric motor 33 which may be directly supported by the base upon which the pump is mounted.

The cranks 16 and 22 are set at such an angle, the latter leading, that the pistons 13 and 19 always have a differential movement, moving in opposite directions to produce the necessary relative differential retreating movement in the region of the inlet port, and the relative differential approaching movement in the region of the outlet port, during a part of the cycle of operations, and moving in the same direction during the remainder of the cycle of operations in order to produce the relative differential traveling movement between the inlet port and the outlet port.

In Fig. 4, the left-hand piston is at its rearmost position while the right-hand piston has already left its foremost position, leaving the inlet port wide open for the admission of a charge to the cylinder. As the pistons move to the right, as indicated by the arrows, but at different speeds, the inlet port closes, Fig. 5, while the outlet port is still covered by the right-hand piston. In Fig. 6, the right-hand piston has reached its rearmost position and the outlet port is wide open. The left-hand piston at this stage

of the cycle of operations has not yet reached its foremost position, so that now the two pistons begin to move in opposite directions, narrowing down the space between their heads as shown in Fig. 7, until finally they touch, as in Fig. 8, thereby expelling the remnant of the charge at the moment of closing the outlet port. The right-hand piston now having passed its mid-return position, both pistons move to the left, Fig. 9, thereby gradually opening the inlet port which will be wide open when they arrive at the end of the return stroke. Further movement of the pistons brings them back to the positions shown in Fig. 4, whereupon the cycle of operations is repeated.

What is claimed is:

1. A valveless pump or compressor comprising a cylinder having an inlet port and an outlet port in its wall, two pistons working in said cylinder, and means for producing relative differential retreating movements of said pistons in the region of said inlet port to draw a charge into said cylinder, and relative differential approaching movements of said pistons in the region of said outlet port to expel a charge from said cylinder, said means including two crankshafts one at either end of said cylinder, a common drive for said crankshafts, and operative connections.
2. A valveless pump or compressor comprising a cylinder having an inlet port and an outlet port in its wall, two pistons working in said cylinder, and means for producing relative differential retreating movements of said pistons in the region of said inlet port to draw a charge into said cylinder, and relative differential approaching movements of said pistons in the region of said outlet port to expel a charge from said cylinder, and relative differential traveling movements of said pistons between said ports and between said retreating and approaching movements, said means including two crankshafts one at either end of said cylinder, a common drive for said crankshafts, and operative connections.

3. A valveless pump or compressor comprising a cylinder having an inlet port and an outlet port in its wall, two pistons working in said cylinder, and two cranks and crankshafts differentially driving said pistons, said cranks being rotative at the same speed but one having a lead over the other.

4. A valveless pump or compressor comprising a cylinder having an inlet port and an outlet port in its wall, two pistons working in said cylinder, a leading crank and a trailing crank and two crankshafts differentially driving said pistons, and means connecting and driving said cranks at the same speed.

5. A valveless pump or compressor comprising a cylinder having an inlet port and an outlet port in its wall, two pistons working in said cylinder, a leading crank and a trailing crank and two crankshafts differentially driving said pistons, and electrically-driven worm-gearing connecting and driving said cranks at the same speed.

6. A valveless pump or compressor comprising a cylinder having an inlet port and an outlet port in its wall, two pistons working in said cylinder, two crankcases supporting said cylinder, a leading crank and a trailing crank respectively working in said crankcases, rods connecting said cranks with said pistons, and electrically-driven worm-gearing connecting and driving said cranks at the same speed.

7. A valveless pump or compressor comprising a cylinder having an inlet port and an outlet port in its wall, two pistons working in said cylinder, two crankcases supporting said cylinder, a leading crank and a trailing crank respectively working in said crankcases, rods connecting said cranks with said pistons, two housings associated with said crankcases, a set of worm-gearing in each housing and driving one of said cranks, and electrically-driven shafts connecting and driving both sets of worm-gearing at the same speed.

In testimony whereof, I have signed my name to this specification.

WILHELM B. BRONANDER.
